To all whom it may concern:

Be it known that I, ALFRED C. The accompanying drawing is an isometric view of the new design for mantels.

The design consists in a mantel substantially of the configuration shown provided 15 with supplemental shelves resembling balconies situated one on each side and near the top of the paneled frame which surmounts the mantel.

Numeral 1 denotes the mantel shelf and 2 20 its columnar supports.

7 denotes the balconies above named. These have each a curved outline provided with a balustrade 8 and surmounts a bracket finial 30 9. At a lower level is a shelf 10 situated centrally in the horizontal plane.

What I claim is—

In testimony whereof I affix my signature 35 in presence of two witnesses.
